US00D867057S

(12) **United States Design Patent** (10) Patent No.: **US D867,057 S**
(45) Date of Patent: ** Nov. 19, 2019

(54) **VESSEL LID**

(71) Applicant: **Base Brands, LLC**, Atlanta, GA (US)

(72) Inventors: **Patrick Spivey**, Atlanta, GA (US);
Kenneth Kreadle, Atlanta, GA (US)

(73) Assignee: **Base Brands, LLC**, Atlanta, GA (US)

(**) Term: **15 Years**

(21) Appl. No.: **29/609,765**

(22) Filed: **Jul. 5, 2017**

(51) LOC (12) Cl. **07-99**

(52) U.S. Cl.

USPC **D7/392; D7/392.1**

(58) **Field of Classification Search**

USPC D9/452, 453, 454, 435, 447, 449;
D7/391, 392, 392.1, 510, 511, 538, 540,
D7/542, 543, 544, 545, 629

(74) Attorney, Agent, or Firm — Park, Vaughan, Fleming & Dowler LLP

(57) **CLAIM**

The ornamental design for a vessel lid, as shown and described.

DESCRIPTION

FIG. 1 is a top perspective view of a first embodiment of my design.

FIG. 2 is a bottom perspective view of the first embodiment.

FIG. 3 is a front view of the first embodiment.

FIG. 4 is a back view of the first embodiment.

FIG. 5 is a top view of the first embodiment.

FIG. 6 is a bottom view of the first embodiment.

FIG. 7 is a right side view of the first embodiment.

FIG. 8 is a left side view of the first embodiment.

FIG. 9 is an exploded, top perspective view of FIG. 1 of the first embodiment.

FIG. 10 is an exploded, right side view of the first embodiment.

FIG. 11 is an exploded, front view of the first embodiment.

FIG. 12 is a top perspective view of a second embodiment of my design.

FIG. 13 is a bottom perspective view of the second embodiment.

FIG. 14 is a front view of the second embodiment.

FIG. 15 is a back view of the second embodiment.

FIG. 16 is a top view of the second embodiment.

FIG. 17 is a bottom view of the second embodiment.

FIG. 18 is a right side view of the second embodiment.

FIG. 19 is a left side view of the second embodiment.

FIG. 20 is an exploded, top perspective view of FIG. 12 of the second embodiment.

FIG. 21 is an exploded, right side view of the second embodiment.

FIG. 22 is an exploded, front view of the second embodiment.

FIG. 23 is a top perspective view of a third embodiment of my design.

FIG. 24 is a bottom perspective view of the third embodiment.

FIG. 25 is a front view of the third embodiment.

FIG. 26 is a back view of the third embodiment.

FIG. 27 is a top view of the third embodiment.

FIG. 28 is a bottom view of the third embodiment.

(Continued)

FIG. 29 is a right side view of the third embodiment.
 FIG. 30 is a left side view of the third embodiment.
 FIG. 31 is an exploded, top perspective view of FIG. 23 of the third embodiment.
 FIG. 32 is an exploded, right side view of the third embodiment; and,
 FIG. 33 is an exploded, front view of the third embodiment. The dashed lines in FIGS. 12, 13, 16, 17, and 20-33 depict portions of the vessel lid that form no part of the claimed design.
